(57) CLAIM

I claim the ornamental design for a bolt-action rifle receiver, as shown and described.

DESCRIPTION

FIG. 1 is a front elevational view of a bolt-action rifle receiver showing my new design;

FIG. 2 is a back elevational view thereof;

FIG. 3 is a right side elevational view thereof;

FIG. 4 is a left side elevational view thereof;

FIG. 5 is a bottom plan view thereof;

FIG. 6 is a top plan view thereof; and,

FIG. 7 is a back perspective view thereof.
